PROCESS OF HANGING PREPASTED
WALLPAPER

William H. Yates, Chicago, and Le Roy W. Staunton, Evanston, Ill., assignors to Trimz Company Inc., Chicago, Ill., a corporation of Delaware

Application April 2, 1943, Serial No. 481,574

2 Claims. (Cl. 216—62)

This invention relates to a new and improved process for applying or hanging prepasted wallpaper to walls and similar surfaces.

The wallpaper rolls to be used with this invention are characterized as being prepasted, whereby the same may be applied to wall surfaces without the necessity of applying paste or other adhesive thereto, but by merely applying water or other moistening liquid to the paste which is already present on the unprinted surface thereof.

It is an object of this invention to provide a new and improved process for applying or hanging prepasted wallpaper to the walls of rooms and the like by the housewife or other unskilled person without requiring the services of a professional or skilled wallpaper hanger.

Other objects not specifically enumerated are contemplated for this invention, as will readily appear to one skilled in the art as the following description proceeds.

The description hereinafter given is to be read in connection with the accompanying drawing, in which—

Figure 1 is an illustration of a roll of wallpaper of the construction employed for the practice of this invention; and

Figure 2 is a figure similar to Figure 1, including, however, an enlarged lateral view of a portion of the roll.

By referring to the drawing, it will be noted that the roll of wallpaper 10 comprises an elongated paper strip 11 which is rolled with the outer decorative or finishing coating 14 thereof on the exterior of the roll instead of on the interior thereof as is the usual practice. Furthermore, it will be noted that the inner surface of the roll is provided with a suitable adhesive or paste 12 applied thereto, which is of such character that the same may be caused to adhere by suitable moistening, such as by applying an adequate amount of water thereto. In addition, the decorative surface is water resistant due to the use of suitable sizing, such as proteins, or by the use of a protective coating 15 of water resistant material, such as varnish.

The roll may be further characterized as having the end of the paper strip which is to be located at the top of the wall, rolled first so that it will come at the core of the roll. This is not necessary, however. The significant features will be apparent from the explanation hereinafter contained of the technique of applying the paper of this roll to a wall surface so that the decorative pattern on the surface of the paper will not

be upside down, nor will it be necessary for the operator to apply the paper from the bottom of the wall upwardly toward the top in order to make the pattern come rightside up.

5 In addition, the roll must be of sufficient width, that is from edge to edge, to provide water-holding space between the convolutions of the roll when the same is rerolled under water, to assure that the adhesive material is moistened at the outset to an extent sufficient to cause it to possess the proper degree of adhesiveness at the time it is later applied to the wall. The significance of these new and improved structural characteristics will now be pointed out.

10 The roll of wallpaper described is especially adapted for use in conjunction with the new and improved technique of applying the paper to the wall surface which constitutes this invention. The technique referred to comprises, first, cutting 15 prescribed lengths of the paper from the roll and, thereafter, rerolling each length so cut so that the end of the cut piece which is to be applied at the top of the wall is rolled in first, or, in other words, at the core of the roll. If the

20 roll is originally supplied with the top of the design located at the core, it will be necessary only to reroll the paper in the same manner that it was originally rolled when supplied. In any event, before moistening the top end of each 25 cut piece must be at the core of the roll. In addition, the rerolling is carried out so that the outside or decorative surface is rolled on the outside of the roll and the paste surface on the inside thereof. With the individual rolls of cut

30 strips thus formed, each in turn is then submerged in a bath, such as cool water contained in a wash basin, wash tub or bath tub, and the same rerolled during the moistening treatment, that is to say, the outer edge of the roll originally

35 submerged forms the core of the new roll, and the paper is then continuously unrolled from the original roll and rerolled on the newly formed roll until the edge that was innermost is exposed as an outer edge. It will be noted that 40 during this rolling operation the operator's hands engage only the outside or decorative part of the paper which is water resistant, and thus the operator avoids contact with the adhesive or paste side of the paper. However, due to the

45 unrolling and rerolling of the paper under water, the entire pre-pasted surface comes in contact with the water and becomes thoroughly moistened. Furthermore, a quantity of water is trapped and held in the convolutions of the roll 50 during the rerolling of the roll in a submerged

condition, so that an adequate amount of water is retained therein to assure that the adhesive or paste remains moist throughout the period of time required for the various operations involved in bringing the paper into proper pasted position on the wall surface.

Inasmuch as the rolling operation, after cutting and prior to moistening, causes the top of the strip to be located at the core of the roll, when the same is rerolled under water the top edge becomes the outer edge. It thus occurs that the top edge is outermost and is readily available for application to the upper edge of the wall surface adjacent the ceiling, picture molding, or other means which defines the upper edge of the wall to be papered.

With the upper edge applied in the proper position, it is only necessary to permit the paper to fall or unroll downwardly under the action of gravity, and by suitable means, such as by the action of a dry or wet sponge, brush or the like, to apply the same to the surface of the wall while working the paper from the top downwardly.

An important aspect of this operation is that the roll, when formed in the manner here described, acts as a spacer between the wall and the new supply of moistened paper coming off of the roll, so that accidental or unwanted contact and adhesion, as when the paper is in an improper position or wrinkled condition, cannot occur, but rather the roll, under the action of gravity and the spacing action of the roll itself, is easily controlled by the operator by applying strokes to the paper as will cause the paper to readily and smoothly engage the wall surface without unwanted or accidental adhesion.

This construction of the roll also permits the operator to support the roll in one hand and in this manner to exercise complete control over it. Merely by lowering the hand supporting the roll, the roll will follow downwardly under the action of gravity while the additional paper automatically rolls therefrom and falls in proper position to be pasted to the wall surface.

It is to be understood that the paper may if desired have one longitudinal edge thereof provided with a selvage 16, in which event the rerolling of the paper preparatory to moistening can be effected through the use of the selvage as a guide. For instance, the rolling can be done with the selvage to the right or left as the case may be, so as to cause the top end to be rolled inwardly at the core. Thus, when the roll is rerolled under water, the top end comes outside. Where a selvage is used, it will be understood that the next adjacent strip of paper will be applied so as to overlap and hide the selvage of the previously applied strip.

If the paper is not sufficiently wide, it has been found that an inadequate amount of moisture will be retained between the convolutions of the roll, with the result that the adhesive or paste may dry out to an undesirable extent before the strip of paper can be applied in adhesive relationship to the wall. Thus it is necessary to have sufficient width to take up an amount of moisture which will assure that the adhesive is maintained moist for the prescribed period, so that there is no danger of the same becoming dry before the applying operation is completed. In practice, it has been found that widths of twelve to fifteen inches and upwardly are sufficient to hold the amount of moisture required for the above described process.

In addition, the adhesive or paste is applied to

the inside of the roll, whereby the prepasted surface is removed from all necessity or liability of touching the same with the hands during the handling operation incident to moistening and applying the same to the wall. Furthermore, by having the paste on the inside surface it is found that the natural camber or bias of the paper with the paste on the concave side, which is created by the dried paste, aids in forming the roll and giving to the paper the resilient bias in the direction of the curve of the roll which enters so satisfactorily into the paper-applying operation.

If desired, the paper of this invention may have markings 17 extending along the length thereof, such as on a selvage edge or on the back, which would indicate unit lengths thereof, such as, for instance, marks placed one foot apart or a yard apart. Such markings would assist the operator in cutting off pieces of the same length without resorting to complicated measuring or matching operations. The markings could be subdivided into fractions of a foot, as may prove to be desirable in any particular case, and the marks can be numbered consecutively, starting from either the inside or outside of the roll. If the numbers start at the center of the roll, the numbers would not only be usable in determining the lengths of each strip, but would also indicate the unused length of any particular roll or part of a roll.

In addition, markings can be provided on the selvage of the paper to indicate which end of the paper should be disposed upwardly when the paper is on the wall. This indication can be supplied by placing arrows on the margin, coupled with a legend stating "This end up" or some similar legend or marking. This type of indication will be particularly useful in instances where the pattern of the paper is such that the upright position may not be readily detected by mere inspection.

We claim:

1. The process of hanging a strip of prepasted paper, which comprises rolling said strip with the end which is to be first applied in at the core of the roll so formed, said rolling operation being characterized in that the prepasted surface is rolled inside, next, submerging the roll so formed in water and unrolling and rerolling the same while it is so submerged, said rerolling operation being characterized in that the prepasted surface is rolled inside and, while the paste is wet, applying the free end of said strip to the starting edge of the surface to be covered and thereafter advancing said roll over said surface and applying pressure to a portion of said paper which is removed from said roll, and causing successive portions of said paper strip to adhere to said surface during the roll advancing operation, and continuing said advancing and applying operations until the entire strip is applied to said surface.

2. The process of hanging a strip of prepasted paper having a selvage on one edge thereof, which comprises rolling said strips with the end which is to be first applied in at the core of said roll while utilizing said selvage as a guide for determining said end, said rolling operation being characterized in that the prepasted surface is rolled inside, next, submerging the roll so formed in water and unrolling and rerolling the same while it is so submerged, said rerolling operation being characterized in that the prepasted surface

is rolled inside and, while the paste is wet, applying the free end of said strip to the starting edge of the surface to be covered and thereafter advancing said roll over said surface and applying pressure to a portion of said paper which is removed from said roll, and causing successive portions of said paper strip to adhere to said

surface during the roll-advancing operation, and continuing said advancing and applying operations until the entire strip is applied to said surface.
